UNITED STATES PATENT OFFICE

158,419

HOLIDAY DETECTOR

Dick E. Stearns, Shreveport, La.

Application May 3, 1948, Serial No. 146,149

Term of patent 14 years

(Cl. D52—1)

To all whom it may concern:

Be it known that I, Dick E. Stearns, a citizen of the United States, residing at Shreveport, in the parish of Caddo, State of Louisiana, have invented a new, original, and ornamental Design for a Holiday Detector, of which the following is a specification, reference being had to the accompanying drawings, forming a part thereof.

In the drawings,

Fig. 1 is a perspective view of a holiday detector showing my new design and illustrating the device in position upon an insulated pipe, the insulated pipe and a rolling electrode surrounding the pipe being shown in phantom in dotted lines and constituting no part of the invention.

Fig. 2 is a front end view of the device shown in Fig. 1.

Fig. 3 is a side elevation of the device shown in

Fig. 1, the other side of the device having the same appearance as does the side illustrated,

Fig. 4 is a top plan view of the device illustrated in Fig. 1, and

Fig. 5 is a rear end view of the device shown in Fig. 1.

I claim:

The ornamental design for a holiday detector, substantially as shown and described.

DICK E. STEARNS.
